UNITED STATES PATENT OFFICE.

JAMES E. DOYLE, OF CLEVELAND, OHIO.

ATTACHMENT FOR PRINTING-PRESSES.

1,164,998.

Specification of Letters Patent. Patented Dec. 21, 1915.

Application filed May 19, 1914. Serial No. 839,514.

To all whom it may concern:

Be it known that I, JAMES E. DOYLE, a citizen of the United States, residing at Cleveland, in the county of Cuyahoga and State of Ohio, have invented a new and useful Improvement in Attachments for Printing-Presses, of which the following is a specification, the principle of the invention being herein explained and the best mode in which I have contemplated applying that principle, so as to distinguish it from other inventions.

This invention termed an attachment for printing presses is more particularly a limiting device for use in conjunction with a Gordon type of press in which a platen is caused to swing toward and away from the type-form.

Those engaged in the art of printing have found it to be very difficult, indeed frequently impossible to produce an impression of uniform color intensity over the entire area of the form. This circumstance is owing to an imparting of various degrees of pressure at different points of contact between the platen and type-form. Such variation in pressure is due either to faulty manufacture, to inaccurate mounting or to an excessively developed loose play of the parts. The latter of these possible causes is the most likely to be responsible and is the factor of imperfection which I have succeeded in overcoming.

Accordingly, my object has been to effect a simultaneous contact throughout the area of the type-form and this I have accomplished by arranging for an independent contact between the platen and bed-frame. In other words, the surface of the form is not of itself intended to terminate the range of approach of the platen. With the aid among else of adjusting means I am enabled to "shim up" the plane of advance of the platen until it lies parallel with the surface of the type-form and thereby consistently obtain long sought results.

The inventive conception is associated with means which are hereinafter explained and variously combined in the claims. While the annexed drawing and particular description thereof, set forth in detail the preferred form embodying my invention, it should be understood that the means only exemplify some of the many diversified mechanical forms with which the principle of my invention may be justly applied.

Adverting to the single sheet of drawing: Figure I is a part section part elevation of a portion of a Gordon type of press showing the platen in position adjacent the type-form and having my invention associated therewith. Fig. II is a mainly horizontal section of Fig. I on an enlarged scale. Fig. III is a perspective view of my inventive type of platen.

A portion of the frame A along the forward edge of which the saddle which carries the inking rollers is adapted to reciprocate, is seen in Fig. I. A pair of brackets a' are included in such frame and their forward surfaces a^2 together form a track upon which the saddles actually roll back and forth. That portion of the frame A which has been shown is formed in the usual manner with a recessed surface known as the bed.

A chase B of any approved form is adapted to snugly fit against the bed a^3 , as shown in Figs. I and II. An insert member b' is in turn adapted to snugly fit and be removable from the chase B. This insert member b' itself supports the form b^2 in which a group of selected type b^3 are mounted. The end or impressing surfaces of the type I have designated with the reference characters b^4 .

A rocker C, shown in both Figs. I and II, carries the platen c' and is so mounted as to be capable of causing the latter to swing toward and away from the type-form. It has not been deemed necessary to illustrate the precise manner in which the rocker C is operatively connected with the press since this is well known to the art and since furthermore nothing whatsoever is claimed in reference thereto. Extending through each of the opposite lateral ends of the platen c' are a pair of screw-threaded openings c^3 , the purpose of which will hereinafter appear. The forward plain surface of the platen I have identified as c^2 . A pad X, usually of cardboard, is shown affixed to the surface c^2 . It is against this padding that the paper stock Y is in brackets held through the agency of a pair of oscillating gripper arms Z. These gripper arms appear in Fig. II, and since the manner in which movement is imparted to them is likewise old, the mode in which they are operatively secured to the press has not been disclosed. It is this surface which has in the past to the best of my knowledge always

had the extent of its approach toward, and hence its degree of pressure as imparted through the padding X and paper stock Y and against the type-form finally prescribed by some portion of the surface of the latter. In assembling the press, the attempt was always made to line up the surfaces b^4 and surface c^2 as accurately as possible. While such attempt was frequently successful, the nicety of adjustment thus accomplished was not maintained after the press had been put in operation, with the result that in due time even very slight disalignments, usually on the part of the platen with respect to the type-form, became at once noticeable in the character of the impressions which were produced. This manifestation consisted in variations in the intensity of the ink over different portions of the impressions and this was of course directly due to greater pressure having been applied to the areas showing the heaviest ink supply.

With the foregoing in mind the utility of the especial feature of my invention to be now described, will be readily understood. I attach a pair of bearing bars D along opposite side ends of the surface c^2 respectively. The attachment of the bars D to the platen c' may be effected by means of a series and in this instance with three screws d' , as clearly seen in Fig. III. I have purposed to have the two bearing bars D adjustably mounted to regulate the advance of the platen by having them contact directly with the frame A and specifically with the surfaces a^2 thereof. Accordingly, instead of having to aline the plane of the surface c^2 I am able to adjust the planes of the bars D with respect thereto until the finished advance surfaces of the bars so limit the effective presentation of the paper stock to the type-form as will insure an absolutely uniform impression over the same. Inasmuch as each of the bars D is separately adjustable and furthermore either end of each one to a greater extent than its opposite end, it should be apparent that the desired uniformity of pressure comes actually with 50 in my control. I have elected to interpose between the under surfaces of bearing bars D and the surface c^2 one or more adjusting strips d^2 depending upon existing requirement. I have furthermore provided set screws d^3 adapted for insertion into the screw threaded openings c^3 and supplied

with additional lock nuts d^4 . When it is desired to adjust one of the bars D the screws d' are to be first loosened, next one or more adjusting strips d^2 either added or removed and finally the set screws d^3 adjusted to compensate for the desired altered position of the bar D after which the screws d' may be again tightened.

My invention being thus described with sufficient thoroughness, what I desire to secure by Letters Patent and therefore claim specifically, is:

1. An attachment for printing presses comprising in combination, a bracket having a pair of flat edge surfaces, a type-form supported therebetween, a platen, means for moving said platen relative to said form, and a pair of flat bearing bars adjustably carried by said platen and adapted to abut said surfaces respectively along their entire length, and set screws for variously effecting the adjustment of said bars with reference to the plane of said platen whereby to limit the approach of said platen toward said type form.

2. An attachment for printing presses comprising in combination, a frame, a type-form supported thereby, a platen, means for moving said platen relative to said form, a pair of elongated bearing bars supported along opposite side edges of said platen, said bars being adapted to engage said frame, and means for independently adjusting different portions of such bars relative to said platen for the useful purpose specified.

3. An attachment for printing presses of the Gordon type comprising in combination, a frame provided along opposite sides with flat tracks, a type-form supported between said tracks, a platen, means for oscillating said platen relative to said form, a pair of elongated bearing bars supported along opposite side edges of said platen and similarly spaced as said tracks, said bars being adapted to engage said frame, and distinct means for independently adjusting opposite ends of each of said bars relative to said platen.

Signed by me, this 30th day of April, 1914.

JAMES E. DOYLE.
